UNITED STATES PATENT OFFICE.

VINCENZO CUTULLI, OF PITTSBURGH, PENNSYLVANIA, ASSIGNOR OF ONE-HALF TO
FRED PERELLA, OF PITTSBURGH, PENNSYLVANIA.

LOCK.

Application filed February 24, 1927. Serial No. 170,545.

The invention relates to locks designed to be opened by a key, but requiring a special manipulation, known only to the owner of the lock. It has for its objects, the provision of a lock of simple reliable construction, presenting great difficulty in unlocking to one lacking a knowledge of its construction, even though such a one has the key, and one which may be used, when desired, 10 in the same way as an ordinary lock, and without any special manipulation. Briefly stated, the invention involves the use of a detent for the bolt, which must be released by a means other than the ordinary use 15 of the key, before such key can be made to function to throw the bolt by the ordinary turning action. In its preferred embodiment, the detent referred to may be released by the key itself, but, only by turning the 20 key upside down and pressing a projection on the key downward to release the detent, but if desired, some other suitable member other than the key may be used to release the detent, such member being inserted 25 through the keyhole to accomplish this result before the key is inserted and turned in the usual way. As a matter of convenience, however, it is preferred to construct the key so that it may be employed to perform the detent-releasing function. One 30 embodiment of the invention is illustrated in the accompanying drawings, wherein:

Figure 1 is a front view of the lock. Fig. 2 is a rear view with the parts in full locked position. Fig. 3 is a rear view with the parts after the detent is released. Fig. 4 is a rear view after the key is turned to move the parts to full unlocked position. Fig. 5 is a rear view after the key is given 40 one turn to bring the parts to partly locking position. Fig. 6 is a partial section on the line VI—VI of Fig. 1 with the key in position releasing the detent. Fig. 7 is a side elevation of the key by itself. And 45 Fig. 8 is a perspective view of one of the springs.

Referring to the drawings, 1 is the face plate of the lock provided with the keyhole 2, and 3 is a hasp having an eye 4 adapted 50 to project through a slot 5 in the face plate. The eye is adapted to receive the bolt 6 of the lock (Fig. 2), the bolt being guided in its movements by the loops 7 and 8 riveted or welded to the face plate. Spaced to 55 the rear of the face plate is the back plate 9,

riveted or bolted to the face plate, and provided with the usual key post 10, upon which the hollow shank of the key 11 pivots when the key is inserted through the keyhole. 60

Lying beneath the back plate, and also secured to the face plate by riveting or welding, is a guide member or sleeve 12 in which the detent 13 is slidably mounted, such detent being provided with a horizontal arm 65 14 lying below the lower end of the keyhole, but accessible therethrough for release as later described. A spring mounted on the pin 15, projecting from the rear of the face plate, and comprising the arms 16 and 17, 70 serves to press the detent 13 yieldingly upward and to press the bolt 6 yieldingly to the left (Fig. 2), the arm 16 being shorter and therefore stiffer than the arm 17. 75

The bolt has, upon its upper side, the locking notches 18 and upon its lower side the abutments 20 and 21 adapted to be engaged under certain conditions by the key, as later described. The spring 22 acts as a locking means for the bolt, its middle portion being provided with a locking shoulder 23 (Fig. 8), which is yieldingly pressed down against the upper side of the bolt. The upper end of the spring is secured to the face plate by the rivet 24, while the lower end is recurved at 25, and lies in the path of the key in its movement of rotation, so that upon such movement the shoulder 23 is released by the key, leaving the bolt free to move to the left (Fig. 2) before the key engages one of the abutments 20 or 21. 80

With the parts in the full locked position of Fig. 2, if the key is inserted and turned counter-clockwise, with reference to Fig. 2, or clockwise with reference to Fig. 1, the bolt 95 6 will not be moved, first because the abutment 21 is too far to the right (Fig. 2) to be reached by the part 26 of the key, and second, because the detent 13 engaging the shoulder 27 on the bolt holds it against movement to the left. The bolt cannot be moved by the key, therefore, until the detent is released and the bolt is moved slightly to the left. 100

In order to release the detent, the key is 105 inserted in the keyhole upside down, as indicated in Fig. 6, with the finger 28 lying inside the face plate 1. If the key is now pressed downward, the detent 13 is moved down against the tension of the spring arm 110

17, thus moving the upper end of the detent out of engagement with the shoulder 27 on the bolt. The release of the detent permits the spring arm 16 to move the bolt 5 6 slightly to the left, the parts now occupying the position shown in Fig. 3.

The bolt may now be moved to full unlocked position by the use of the key in the ordinary way. The key is therefore inserted 10 so that its hollow shank engages the post 11 and is turned in a counterclockwise direction, Fig. 3. The part 26 of the key first strikes the lower end 25 of the spring 22, moving such spring upward so that the 15 shoulder 23 is disengaged from the notch 18 on the bolt. A further movement of the key brings the part 26 into engagement with the abutment 21, the movement of the bolt to the left under the influence of the spring 20 arm 16, heretofore referred to, having brought such abutment within reach of the part 26 of the key. The continued movement of the key serves to move the bolt to complete open position, as indicated in Fig. 25 4, the eye 4 of the hasp thus being released.

To move the bolt again to locking position, the key is inserted in the normal way and given one complete rotation in a clockwise direction, the part 26 of the key during such 30 rotation engaging the abutment 20 and moving the bolt to the position of Fig. 5. This movement of the bolt is not sufficient to bring the shoulder 27 far enough to the right to be engaged by the detent, but is far enough to 35 cause the bolt to engage the eye 4 of the hasp. The lock may now be unlocked in the normal way, by merely turning the key in a counterclockwise direction, during which the part 26 engages the abutment 21 and moves the 40 parts back to the position of Fig. 4. The lock may therefore be used, when desired, in the same manner as an ordinary lock, without bringing the detent 13 into play.

To completely lock the bolt by bringing 45 the detent into play and causing the parts to again assume the position of Fig. 2, the key, after bringing the parts to the position of Fig. 5, is given a second movement of rotation in a clockwise direction. The key, during 50 this movement of rotation, engages the second abutment 21 on the bolt and moves the bolt to the right to the position of Fig. 2. This movement places both of the spring arms 16 and 17 under tension, the tension in 55 the arm 17 causing the detent 13 to move up and engage the bolt behind the shoulder 27, thus completing the cycle, so that the bolt cannot be again moved to unlocking position without first releasing the detent as heretofore described.

It will be apparent that the invention is not limited to the particular embodiment shown. It is applicable to almost any lock employing a bolt and a key, and the details 60 of the mechanism may be varied widely de-

pending on the type of lock to which the invention is applied. If desired, the detent may be released by some means other than a finger forming a part of the key, as heretofore pointed out, although this construction 70 is preferred.

What I claim is:

1. In combination in a lock adapted to be locked and unlocked by a key, a face plate provided with a keyhole, a bolt adapted to be reciprocated by the rotation of the key, and a detent out of reach of the key during the normal rotary movement of such key in either direction engaging the bolt and positively holding it against unlocking movement by the key, the said detent being accessible for actuation by means inserted through the keyhole.

2. In combination in a lock adapted to be locked and unlocked by a key, a face plate provided with a keyhole, a bolt adapted to be reciprocated by the rotation of the key, a detent out of the reach of the key during the normal rotary movement of the key in either direction engaging the bolt and positively holding it against unlocking movement by the key, and a spring for moving the bolt far enough toward unlocked position when the detent is released to permit such bolt to be engaged and moved to full unlocked position by the key, the said detent being accessible for release by means inserted through the keyhole.

3. In combination in a lock adapted to be locked and unlocked by a key, a face plate provided with a keyhole, a bolt provided with two locking abutments so that two rotations of the key are required to move it to completely closed position, a detent for engaging and positively locking the bolt against opening movement when it reaches full closed position, a spring under tension tending to move the bolt to partly unlocked position when the detent is released, the said bolt having one of said abutments located so that one rotation of the key will open it from said partly unlocked position, and said detent being accessible for actuation by means inserted through the keyhole.

4. In combination in a lock adapted to be locked and unlocked by a key, a face plate provided with a keyhole, a bolt provided with two locking abutments so that two rotations of the key are required to move it to completely closed position, a detent for engaging and positively locking the bolt against opening movement when it reaches full closed position, a spring under tension tending to move the bolt to partly unlocked position when the detent is released, the said bolt having its abutments located so that a rotation of the key in one direction will move it from said partly unlocked position to completely locked position, and a rotation in the other direction from said partly un-

locked position will completely unlock it, the said detent being accessible for actuation by means inserted through the keyhole.

5. In combination in a lock adapted to be locked and unlocked by a key, a face plate provided with a keyhole, a bolt provided with two locking abutments so that two rotations of the key are required to move it to completely closed position, a detent for engaging and positively locking the bolt against opening movement when it reaches full closed position, a spring under tension tending to move the bolt to partly unlocked position when the detent is released, the said

bolt having its abutments so located that a 15 rotation of the key will move it from said partly unlocked position to completely unlocked position, and so that a reverse rotation from said completely unlocked position will move it to said partly locked position, 20 the said detent being accessible for actuation by means inserted through the keyhole preliminary to the rotation of the key.

In testimony whereof, I have hereunto subscribed my name this 19th day of February, 1927. 25

VINCENZO CUTULLI.
